UNITED STATES PATENT OFFICE.

EUGÉNE CHASSAING, OF PARIS, FRANCE, ASSIGNOR TO MARCEL DUFOUR, EMILE JACQUELIN, AND RENÉ ACHILLE HENRY, OF PARIS, FRANCE.

AMBULANCE-STRETCHER.

1,277,856.

Specification of Letters Patent.

Patented Sept. 3, 1918.

Original application filed February 3, 1916, Serial No. 75,951. Divided and this application filed April 5, 1917. Serial No. 160,068.

To all whom it may concern:

Be it known that I, EUGÉNE CHASSAING, a citizen of France, and a resident of Paris, France, have invented a new and Improved 5 Ambulance-Stretcher, of which the following is a full, clear, and exact description.

My invention relates to ambulance stretchers, of which this is a divisional application of my patent application, Serial No. 75,951, 10 filed February 3, 1916. An object thereof is to provide a stretcher the flexible fabric of which can be easily and quickly detached from the poles without disturbing a wounded person resting thereon. Another object 15 of the invention is to adapt my stretcher to the existing types of stretchers.

With the above and other objects in view, the nature of which will more fully appear as the description proceeds, the invention 20 consists in the novel construction, combination and arrangement of parts as herein fully described, illustrated and claimed.

In the accompanying drawings, forming part of the application, similar characters 25 of reference indicate corresponding parts in all the views.

Figure 1 is a plan of the stretcher embodying my invention;

Fig. 2 is a cross section through the 30 stretcher embodying my invention; and

Fig. 3 is a similar cross section showing a modified structure of the stretcher.

Referring to the drawings, 4 is a flexible fabric, suitable for the purpose, which is 35 provided at each longitudinal edge with a hem 5. Each of the hems receives a flexible beading 6 formed of any suitable material, such, for example, as cord, leather or spiral spring.

40 The beading surrounded by the hem fits easily into a socket 7 through an end of the socket. Each of the sockets has a longitudinal slot 9 extending through the entire length thereof to allow the flexible fabric to 45 pass therethrough when the beads of the fabric are fitted into the sockets. The width of the slot is considerably less than the diameter of the beads, so there is no chance for the beads to be pulled through said slot.

50 The length of the socket is substantially the same as that of the fabric. Each of the

sockets is secured to the outer side of a pole 8 by any suitable means.

In Fig. 2 the sockets are made of two independent tube segments, each being flanged 55 at the edge where it is to be secured to the pole.

In Fig. 3 the sockets are also formed of two tubular segments, but an additional plate 10 is provided to which the segments 60 are previously secured, and which plate is then secured to the pole.

I claim:

1. A stretcher comprising a pair of poles, a flexible fabric having hems on its longitudinal edges, a flexible beading in each of the hems, and a slotted socket on each of the poles adapted to receive a hem of the fabric with the bead therein. 65

2. A stretcher comprising two longitudinal poles, a flexible fabric having a hem on each of its longitudinal edges, a flexible beading for each of the hems, and a socket secured to each of the poles for receiving a hem of the fabric with the bead therein, 70 said socket being formed of a pair of tubular segments presenting an opening on the outer side for the fabric to pass therethrough when the hem and bead engage the segments forming the socket. 75

3. A stretcher comprising two longitudinal poles, a flexible fabric having a hem on each of its longitudinal edges, a flexible bead in each of the hems, and a socket secured to each of the poles for receiving a hem of 80 the fabric with the bead therein, said socket being formed of a pair of tubular segments spaced to present an opening on the outer side for the fabric to pass therethrough, said segments having a flange whereby said 85 segments may be secured to form the desired opening for the fabric.

4. A stretcher, comprising a pair of poles, slotted sockets secured to the outer sides of the poles and terminating short of the ends 90 of the poles, and a flexible fabric having at its longitudinal edges beads slidably freely in the said sockets. 95

EUGÉNE CHASSAING.
